UNITED STATES PATENT OFFICE.

BENJAMIN K. HALL, OF MERRIMAC, MASSACHUSETTS, ASSIGNOR OF ONE-HALF TO
BEN T. PICKARD, OF HAVERHILL, MASSACHUSETTS.

SIGNALING DEVICE FOR MOTOR-VEHICLES.

1,234,157.

Specification of Letters Patent. Patented July 24, 1917.

Application filed April 13, 1916. Serial No. 91,500.

To all whom it may concern:

Be it known that I, BENJAMIN K. HALL, a citizen of the United States of America, and a resident of Merrimac, in the county of Essex and State of Massachusetts, have invented certain new and useful Improvements in Signaling Devices for Motor-Vehicles, of which the following is a specification.

This invention relates to signaling devices for motor cars and particularly to devices of this character which are adapted to indicate the direction in which the car is about to be turned.

The object of the invention is to provide a simple but effective means whereby the direction in which the car is to be turned may be indicated to the drivers of approaching cars and also to the drivers of cars following.

The invention consists in a pivoted member of peculiar construction and normally hidden which is under the control of the driver of the car and which may be moved outwardly into an exposed position when desired.

The invention further consists in certain novel features of construction and arrangement of parts which will be fully understood by reference to the description of the drawings and to the claims hereinafter given.

For the purpose of illustrating the invention, one preferred form thereof is illustrated in the drawings, this form having been found to give satisfactory and reliable results, although it is to be understood that the various instrumentalities of which the invention consists can be variously arranged and organized, and that the invention is not limited to the precise arrangement and organization of these instrumentalities as herein shown and described.

Of the drawings:

Figure 1 represents an elevation of a portion of a car showing a device attached thereto embodying the principles of the present invention.

Fig. 2 represents a front elevation of the same.

Fig. 3 represents an elevation of the signal thereof. 50

Fig. 4 represents an edge view of the same. 55

Fig. 5 represents a vertical section of the same in its normal position. 55

Fig. 6 represents a similar view in operative position. 60

Fig. 7 represents an elevation of the lower end of the pivoted signal lever and its support. 60

Fig. 8 represents a side elevation of the same in its normal position. 65

Fig. 9 represents a similar view when the signal lever has been moved into its operative position, and 65

Fig. 10 represents an elevation of the operating handle for controlling the movement of said signal lever. 70

Similar characters designate like parts throughout the several figures of the drawings. 70

In the drawings, 10 represents a portion of the body of a motor car having an upright 11 secured thereto at one side of the usual wind shield 12. Clamped or otherwise secured to the upright 11 is a container 13 having its outer side opened as indicated in Fig. 1 of the drawings. Normally positioned within the container 13 is a forked member 14 having a flat plate 15 pivotally mounted therein at 16. 75

The forked member 14 is secured to the end of a tubular member or lever 17, the lower end of which is pivoted at 18 to a support 19 secured to a side of the body of the car. The lever 17 is provided with an outwardly extending arm 20 from which a wire 21 extends through a pliable pipe 22 to an operating handle 23 pivoted at 24 to a bracket 25 mounted on the car at a point 90 accessible to the driver thereof. 85

A spring 26 is interposed between the bracket 25 and the operating handle 23, this spring serving to retain the handle in its normal position, as indicated in Fig. 10 of 95 the drawings, or in its abnormal position, as indicated in dotted lines in the same figure.

When the handle 23 has been moved from its normal position as shown in Fig. 10 of the drawings into the position shown in dotted lines, the flexible connector 21 will be drawn through the pipe 22, thereby causing the lever 17-20 to be moved about its pivot 18 into the position indicated in dotted lines in Fig. 2 of the drawings.

A flexible member 27 extends through the tubular member 17 and has one end thereof secured to the support 19 at 28 while its opposite end is secured to a pin 29 extending laterally from the plate 15 at one side of the pivot thereof. Normally the plate 15 extends longitudinally of the forked member 14, but when the lever 17-20 is moved into the position indicated in dotted lines in Fig. 2 of the drawings, the plate 15 will be moved about the pivot 16 until it is perpendicular to the member 14, thereby forming a cross, as indicated in Fig. 6 of the drawings.

The support 19 is provided with a coiled spring 30, one end of which is attached at 31 to the arm 20, this spring having sufficient tension to return the lever 17-20 to its normal position when the operating handle 23 has been moved about its pivot 24 to the position shown in full lines in Fig. 10 of the drawings.

About the pivot 16 is a spring 32 which is adapted to move the plate 15 about the pivot 16 and return it to a position in alignment with the tubular member 17. The return movement of the plate 15 about its pivot 16 is limited by means of the stop member 33, as shown in Figs. 3, 4, 5, and 6 of the drawings.

While in the drawings a signal device is shown for only one side of the car, it is obvious that the same construction should be repeated for the other side of the car. The signal formed of the U-shaped member 14 and the pivoted plate 15 is painted red for one side of the car, and green for the other. When the chauffeur is about to turn his car in either direction, he seizes the proper operating handle 23 and moves it about its pivot to throw the signal lever 17-20 into the position shown in dotted lines on Fig. 2 of the drawings. While in this position it is exposed to view to cars coming in either direction.

Another advantage of the device is that when the signal is moved into its operative position it indicates to the traffic officer the direction in which the driver of the car desires to turn.

It is believed that the operation and many advantages of this invention will be fully apparent from the foregoing description.

Having thus described my invention, I claim:

1. In a device of the class described, the combination of a fixed support; a swinging lever pivotally mounted thereon; a fixed

plate secured to the outer end thereof; a movable plate pivoted to said fixed plate; and means operable by the swinging of said lever for moving said pivoted plate relatively to said fixed plate.

2. In a device of the class described, the combination of a fixed support; a swinging lever pivotally mounted thereon; a fixed plate secured to the outer end thereof; a movable plate pivoted to said fixed plate; means operable by the swinging of said lever for moving said pivoted plate relatively to said fixed plate; and a spring adapted to return said pivoted plate to its normal position.

3. In a device of the class described, the combination of a fixed support; a swinging lever pivotally mounted thereon; a fixed plate secured to the outer end thereof; a movable plate pivoted to said fixed plate; means operable by the swinging of said lever for moving said pivoted plate relatively to said fixed plate; and a stationary container adapted to inclose said plates when not in use.

4. In a device of the class described, the combination of a fixed support; a tubular member pivotally mounted thereon and adapted to swing about its pivot; a fixed plate secured to the outer end thereof; a movable plate pivoted to said fixed plate; and a connector extending through said tubular member and attached at one end to said pivoted plate and at the other to said fixed support.

5. In a device of the class described, the combination of a fixed support; a swinging lever pivotally mounted thereon; a fixed plate secured to the outer end thereof and provided with a lateral projection; a movable plate pivoted to said fixed plate and normally in contact with said projection; and means operable by the swinging of said lever for moving said pivoted plate relatively to the projection on said fixed plate.

6. In a device of the class described, the combination of a fixed support; a swinging lever pivotally mounted thereon; a fixed plate secured to the outer end thereof; a movable plate pivoted to said fixed plate; means operable by the swinging of said lever for moving said pivoted plate perpendicularly to said fixed plate; means for moving said lever from its normal position; and a spring for returning said lever to its normal position.

7. In a device of the class described, the combination of a fixed support; a swinging lever pivotally mounted thereon; a fixed plate secured to the outer end of said lever; a movable plate pivoted midway of its length to said fixed plate; and means operable by the swinging of said arm for moving said movable plate perpendicularly to said fixed plate.

8. In a device of the class described, the combination of a fixed support; a swinging lever pivotally mounted thereon; a fixed plate secured to the outer end of said lever; a movable plate pivoted midway of its length to said fixed plate at a point substantially midway of the length of the latter and means operable by the swinging of said

arm for moving said movable plate perpendicularly to said fixed plate.

10

Signed by me at 4 Post Office Sq., Boston, Mass., this 7th day of April, 1916.

BENJAMIN K. HALL.
